14 Claims. (Cl. 62—119.5)

1

This invention relates to refrigeration, and is concerned with cooling separate compartments of a household refrigerator with the aid of cooling elements operable at different temperatures. More particularly, the invention is concerned with cooling subdivided compartments of a refrigerator with the aid of absorption refrigeration apparatus of the inert gas type having a low temperature cooling element and a higher temperature cooling element.

It is an object of the invention to provide an improvement for cooling separate compartments of a household refrigerator by cooling elements operable at different temperatures, particularly to effect cooling of each compartment by a cooling element having a refrigerant passage which is disposed essentially in a single vertical plane. This may be accomplished by providing cooling elements formed of looped coils, each looped coil having straight portions and connecting bends disposed essentially in a single vertical plane, and positioning such looped coils operable at different temperatures alongside one another in separate compartments at opposite sides of a vertical partition, or one above the other in the same vertical plane at opposite sides of a horizontal partition.

Another object of the invention is to provide an improved household refrigerator, having a number of compartments which are cooled by cooling elements of an absorption refrigeration system of the inert gas type, wherein one compartment serving as a freezing section is cooled by a vertically disposed cooling element which extends for a major distance of the height of such freezing section. This is accomplished by providing a low temperature cooling element for the freezing section which comprises a looped coil having straight portions and connecting bends in a single vertical plane, and desirably includes a vertical wall member in good thermal relation with the looped coil which provides a relatively extensive heat transfer surface, and also horizontal plates heat conductively connected to the coil straight portions for supporting ice trays and other matter to be frozen. The wall member of the cooling element may serve as a side wall of the freezing section and promotes maintaining a substantially constant temperature throughout all regions, thereby avoiding a steep vertical temperature gradient in the freezing section.

The above and other objects of the invention will be more fully understood upon reference to the following description and accompanying drawings forming a part of this specification, and of which:

2

Fig. 1 more or less diagrammatically illustrates an absorption refrigeration system of the inert gas type embodying the invention;

Fig. 2 is a top plan view of the cooling unit of Fig. 1 to illustrate the connections to the upper part thereof more clearly;

Fig. 3 is a fragmentary view of the refrigeration system shown in Fig. 1 to illustrate details more clearly;

10 Fig. 4 is a view similar to Fig. 1 illustrating another embodiment of the invention;

Fig. 5 is a top plan view of the cooling unit of Fig. 4 to illustrate the connections to the upper and lower ends thereof more clearly;

15 Fig. 6 is a view of the cooling unit taken at line 6—6 of Fig. 4;

Fig. 7 is a view similar to Figs. 1 and 4 illustrating a further embodiment of the invention;

Fig. 8 is a side vertical sectional view of a refrigerator and parts of a refrigeration system associated therewith which is generally like that shown in Fig. 1;

20 Fig. 9 is a front elevation of the refrigerator illustrated in Fig. 8, the front door or closure member therefor being omitted;

Fig. 10 is a side vertical sectional view of a refrigerator and parts of a refrigeration system associated therewith which is generally like that shown in Fig. 4;

30 Fig. 11 is a front elevation of the refrigerator illustrated in Fig. 10, the front door or closure member therefor being omitted;

Fig. 12 is a side vertical sectional view of a refrigerator and parts of a refrigeration system generally like that shown in Fig. 7; and

35 Fig. 13 is a front elevation of the refrigerator illustrated in Fig. 12, the front door or closure member therefor being omitted.

Referring to Fig. 1, the invention is embodied 40 in an absorption refrigeration system of a uniform pressure type in which an inert gas or auxiliary pressure equalizing fluid is employed. In a system of this type a refrigerant fluid, such as liquid ammonia, for example, is introduced into an evaporator structure or cooling unit 14 from a condenser 15 in a manner which will be explained presently. The refrigerant fluid evaporates and diffuses in cooling unit 14 into an inert gas, such as hydrogen, for example, to produce a refrigerating effect.

45 The resulting gas mixture of refrigerant and inert gas flows from the cooling unit 14 through an outer passage 16 of a gas heat exchanger 17 and vertical conduit 18 into an absorber comprising a vessel 19 and a looped coil 20. In the absorber vessel 19 and coil 20 refrigerant vapor

is absorbed by a suitable absorbent, such as water, for example, which is introduced into coil 20 through a conduit 21. The hydrogen or inert gas, which is practically insoluble and weak in refrigerant, returns to the cooling unit 14 through an inner passage 22 of gas heat exchanger 17 and a conduit 23.

From the vessel 19 enriched absorption liquid flows through a conduit 24 and an inner passage 25 of a liquid heat exchanger 26 into the lower end of a vapor liquid lift tube 27 of a generator unit 28. The generator or vapor expulsion unit 28 comprises a heating tube 29 having the vapor lift tube 27 and a boiler pipe 30 in heat conducting relation therewith, as by welding, for example. By heating generator unit 28, as by an electrical heating element or a gaseous or liquid fuel burner (not shown), liquid is raised by vapor lift action through tube 27 into the upper part of boiler pipe 30. The liberated refrigerant vapor entering boiler pipe 30 through tube 27, together with vapor expelled from solution in the pipe 30, flows upwardly into an air-cooled rectifier 31 and thence into the condenser 15 which may be air-cooled and provided with heat dissipating members (not shown). Refrigerant vapor is liquefied in the condenser 15 and returns to the cooling unit 14 to complete the refrigerating cycle, as will be explained presently. The weakened absorption liquid, from which refrigerant vapor has been expelled, is conducted from boiler pipe 30 through a conduit 32, outer passage 33 of liquid heat exchanger 26 and conduit 21 into the upper part of the absorber coil 20.

In accordance with this invention, the cooling unit 14 comprises two vertically disposed cooling elements 14a and 14b which are operable at different temperatures and adapted to be positioned in a thermally insulated interior of a refrigerator cabinet for cooling several compartments therein. In the embodiment of Figs. 1 and 2, the vertically extending cooling elements 14a and 14b are in the form of looped coils positioned alongside one another and each of which is disposed in a single substantially vertical plane.

The cooling elements 14a and 14b are connected to one another and to the gas heat exchanger 17 in such manner that inert gas weak in refrigerant flows from the upper end of absorber coil 20 through the inner passage 22 of the gas heat exchanger and conduit 23 into the upper end of cooling element 14a. After flowing downwardly through cooling element 14a, inert gas passes through a conduit 34 connecting the lower ends of the cooling elements and then flows upwardly through the cooling element 14b. From the upper end of cooling element 14b inert gas passes through a conduit 35 into the outer passage 16 of the gas heat exchanger.

Liquid refrigerant is supplied from condenser 15 to the upper ends of cooling elements 14a and 14b through conduits 36 and 37, respectively. Hence, liquid refrigerant flows downwardly in cooling element 14a in parallel flow with inert gas and downwardly in cooling element 14b in counterflow to inert gas passing upwardly therethrough. Refrigerant vapor from the generator unit 28 flows successively through condenser sections 15a, 15b and 15c, and refrigerant vapor liquefied in condenser section 15b flows therefrom through conduit 36 to the upper end of cooling element 14a. Refrigerant vapor which is not liquefied in condenser section 15b then passes into condenser section 15c and condenses therein, and such condensate flows there-

from through conduit 37 to the upper end of cooling element 14b.

In order to insure liquid refrigerant being supplied to the upper end of cooling element 14b when air cooling of condenser 15 is employed and the temperature of the air is relatively low, under which conditions there is a tendency for a greater part of the refrigerant vapor to be liquefied in condenser sections 15a and 15b, a conduit 38 is provided to divert liquid refrigerant from condenser section 15a into condenser section 15c, such conduit including a trap so that a liquid seal will form therein. In this way a supply of liquid refrigerant to cooling element 14b from condenser section 15c is insured when the quantity of refrigerant vapor liquefying in that condenser section is substantially reduced due to low temperature air cooling of the condenser 15.

Any unevaporated refrigerant passes from the lower ends of cooling elements 14a and 14b into one leg of a U-shaped conduit 39 whose opposite leg is connected to the absorber vessel 19 at a region which is below the normal liquid level therein. In order to insure draining of unevaporated liquid from the cooling unit 14, the conduit 39 is desirably connected to the lowest point thereof which may be at either of the cooling elements 14a or 14b or the cross connection 34 therebetween.

Since the inert gas flows successively through the cooling elements 14a and 14b, the gas in the cooling element 14a contains a lesser amount of refrigerant vapor than in the cooling element 14b. The partial vapor pressure of the refrigerant is a gradient, so that the temperature of liquid refrigerant in the cooling elements is also a gradient, the evaporating temperature of liquid being lower in the cooling element 14a which constitutes the freezing section of the cooling unit. In order to reduce and lower the mean or average temperature of cooling element 14a, the conduit 36 through which liquid refrigerant is supplied to that cooling element is arranged in thermal exchange relation with the upper part of cooling element 14b, as best seen in Fig. 2. With this arrangement the relatively cool gas mixture of refrigerant vapor and inert gas, which is about to pass from the upper end of cooling element 14b, is effectively utilized to abstract heat from liquid refrigerant in conduit 36 prior to entering the low temperature cooling element 14a.

In order to simplify Figs. 1 to 3, the cooling unit 14 has been illustrated apart from a household refrigerator. One manner in which the cooling elements 14a and 14b of an absorption refrigeration system like that just described may be positioned in a thermally insulated interior of a household refrigerator cabinet for cooling separate compartments therein is diagrammatically illustrated in Figs. 8 and 9. In Figs. 8 and 9 the cooling unit 14 is disposed in a cabinet 40 having a space 41 defined by an inner liner or shell 42 which is arranged to be supported within an outer metal shell 43 and insulated therefrom with any suitable insulating material 44. The space 41 is provided with a front access opening 45 which is adapted to be closed by an insulated door or closure member (not shown) hinged to the front of the cabinet 40.

In order to position the cooling unit 14 in the space 41, the rear wall 46 of the cabinet 40 is formed with an opening 47 defined by a rectangular frame 48 which is formed of material

having poor heat conducting properties. A cover or closure member 49 for the opening, which contains insulating material 50 and through which the gas heat exchanger 17 and conduits 36, 37 and 39 extend, is arranged to bear against gaskets 51 and 52 of suitable insulating material and removably secured in any suitable manner (not shown) to the rear wall 46. The cabinet 40 is provided with a vertically extending compartment 53 at the rear thereof in which the generator unit 28, condenser 15, absorber vessel 19 and coil 20, and conduits connecting these parts are housed in a well known manner.

In accord with the invention, the low and higher temperature cooling elements 14a and 14b are located at opposite sides of a vertical wall member 54 in the space 41 which subdivides the latter into compartments 55 and 56. The wall member 54 may be formed of suitable insulating material or spaced apart metallic plates having insulation therebetween and serves as a thermally insulated partition between the compartments 55 and 56.

The cooling or refrigerating effect produced by the low temperature cooling element 14a is utilized to effect cooling of the compartment 55 which may be referred to as a freezing section adapted to receive ice trays 57, frozen food packages and other matter to be frozen. In order to support ice trays in good thermal contact with the straight portions of the looped coil forming cooling element 14a, plates 58 or other structure may be arranged in heat conducting relation with such straight portions to provide suitable tray supporting surfaces. Such plates 58 may be heat conductively connected to a vertical wall member 58a which serves as a side wall of the compartment 56. The access opening of the freezing compartment 56 at the forward part thereof may be provided with a hinged door (not shown) desirably formed of transparent material which may be spring biased to its closed position in any suitable manner and readily opened by grasping a part thereof.

The cooling effect produced by the higher temperature cooling element 14b is utilized to cool air in the compartment 55 and abstract heat from food products which may be stored therein on suitable shelving indicated in dotted lines at 59 in Fig. 9. The vertically disposed looped coil forming the higher temperature cooling element 14b desirably is provided with a housing 60 fabricated of material having good heat conducting properties to promote effective cooling of the compartment 55, and the cooling element 14b may be in good thermal contact with the side wall of the housing 60 directly opposite a side wall of the inner shell 42.

By providing vertically disposed cooling elements 14a and 14b which occupy a major portion of the height of the compartments 55 and 56 and extend downwardly from regions closely adjacent to the top walls thereof, efficient cooling of the compartments is effected and cooling temperatures are produced therein which are more or less uniform in all parts thereof. This is especially important in the freezing compartment 56 in which a steep vertical temperature gradient is undesirable, because all parts thereof should be made available for storing frozen food packages and the like at a sufficiently low freezing temperature without any danger of thawing taking place.

A further advantage of the vertical disposition of cooling elements 14a and 14b in single vertical

planes closely adjacent to one another is that an opening 47 of minimum size is required at the rear wall 46 for inserting the cooling unit 14 into the storage space 41. In this way the tendency for heat transfer into the compartments 55 and 56, about the closure member 49 which closes the opening, is materially reduced and efficient cooling by the cooling elements 14a and 14b is promoted. The housing 60 for the higher temperature cooling element 14b may be removably secured thereto after the cooling unit 14 is located in the space 41, and to this end suitable clamping means may be provided at the interior of the housing to establish a good heat conducting connection between the higher temperature coil and side wall of the housing, thereby providing a relatively extensive heat transfer surface for cooling air in the compartment 55.

In Figs. 4 to 6 another embodiment of the invention is illustrated which differs from the embodiment just described in that the lowest point of the cooling unit is substantially at the same level or immediately above the highest point of the absorber. In Figs. 4 to 6 parts similar to those shown in Figs. 1 to 3 are referred to by the same numerals increased by one hundred. As in the first described embodiment, the cooling elements 114a and 114b in Figs. 4 to 6 are in the form of looped coils positioned alongside one another, each coil being disposed in a single substantially vertical plane.

The cooling elements 114a and 114b are connected to one another and to the gas heat exchanger in such manner that inert gas weak in refrigerant flows from the absorber coil 120 through the inner passage 122 of the gas heat exchanger 117 into the lower end of the low temperature cooling element 114a. After flowing upwardly through cooling element 114a, inert gas passes through a conduit 134 connecting the upper ends of the cooling elements and then flows downwardly through the higher temperature cooling element 114b. From the lower end of cooling element 114b inert gas enriched in refrigerant passes through a conduit 135 into the outer passage 116 of the gas heat exchanger, as best seen in Fig. 5.

Liquid refrigerant is supplied from condenser 115 to the upper ends of cooling elements 114a and 114b in the same manner that refrigerant is delivered from condenser 15 to cooling elements 14a and 14b in the embodiment first described. Accordingly, liquid refrigerant is delivered through conduit 136 to the upper end of low temperature cooling element 114a, and refrigerant is conducted through conduit 137 to the upper end of higher temperature cooling element 114b. The refrigeration system being described differs from the embodiment first described in that liquid refrigerant flows downwardly in cooling element 114a in counterflow to inert gas and downwardly in cooling element 114b in parallel flow with inert gas. Any unevaporated refrigerant which flows from the lower ends of cooling elements 114a and 114b passes into the outer passage 116 of the gas heat exchanger and drains by gravity back to the absorber vessel 119.

In order to effect precooling of liquid refrigerant supplied through conduit 136 to the cooling element 114a, this conduit is arranged in heat exchange relation with the upper part of cooling element 114b, as shown in Figs. 5 and 6. A dam or barrier 161 is provided in the conduit 134, as shown in Fig. 4, so that liquid refrigerant sup-

plied to each cooling element will not be diverted into the other cooling element. Since the inert gas flows successively through the cooling elements 114a and 114b and the gas in cooling element 114a contains a lesser amount of refrigerant vapor than in cooling element 114b, the cooling element 114a will operate at a lower temperature than cooling element 114b and constitutes the freezing section of the cooling unit 114.

One manner in which the cooling elements 114a and 114b of an absorption refrigeration system like that just described may be positioned in a thermally insulated interior of a household refrigerator cabinet for cooling separate compartments therein is diagrammatically illustrated in Figs. 10 and 11. In Figs. 10 and 11 parts corresponding to those shown in Figs. 8 and 9 are designated by the same reference numerals increased by one hundred. In Figs. 10 and 11 the space 141 is divided into compartments 155 and 156 by a vertical partition 154 which extends downwardly from the top of the space and a horizontal partition 162 which extends from a side wall of the inner shell 142 and is joined to the lower end of the vertical partition. The partitions 154 and 162 may be formed of suitable insulating material for thermally shielding the compartments 155 and 156 from one another.

The low temperature cooling element 114a is located at one side of the vertical partition 154 in the compartment 156, and the refrigerating effect produced by this cooling element is utilized to cool compartment 156 which is employed as a freezing section. As described above in connection with Figs. 8 and 9, the compartment 156 may be provided with a hinged closure member (not shown) to gain access therein and keep the freezing section closed to maintain a low temperature therein.

The higher temperature cooling element 114b is located at the opposite side of the vertical partition 154 in the compartment 155, and the refrigerating effect produced by this cooling element is utilized to cool air and abstract heat from food products which may be disposed on shelving indicated in dotted lines at 159 in Fig. 11. As in the previously described embodiment, the cooling element 114b may be concealed in a shell or housing 160 and desirably in heat conducting relation therewith.

By locating the cooling elements 114a and 114b closely adjacent to each other at opposite sides of the vertical insulated partition 154, a compact cooling unit is provided which occupies a minimum amount of space and requires an opening at the rear wall 146 which is relatively small for inserting the cooling unit into the interior of the refrigerator cabinet 140.

In Fig. 7 a further embodiment of the invention is illustrated in which the low and higher temperature cooling elements are disposed in the same vertical plane one above the other for cooling separate compartments in a thermally insulated interior of a refrigerator cabinet. In Fig. 7 parts corresponding to those in the first described embodiment are referred to by the same reference numerals increased by two hundred. In Fig. 7 the cooling elements 214a and 214b are in the form of looped coils positioned one above the other in the same vertical plane, and a gas heat exchanger 263 is interposed between the looped coils.

The cooling elements 214a and 214b are connected in the gas circuit in such manner that inert gas weak in refrigerant flows from the upper end of the absorber coil 220 through a conduit

264, outer passage 216 of gas heat exchanger 217 and conduit 223 into the outer passage 265 of the gas heat exchanger 263. From the gas heat exchanger passage 265 inert gas flows upwardly through low temperature cooling element 214a and leaves the latter through a conduit 266. The conduit 266 is in the form of a looped coil which is in the same vertical plane as the cooling elements 214a and 214b and a portion thereof serves as the inner passage of the gas heat exchanger 263. The lower end of conduit 266 communicates with the upper end of the cooling element 214b, and, after inert gas passes downwardly through such cooling element, inert gas rich in refrigerant flows through the inner passage 222 of gas heat exchanger 217 to the absorber vessel 219.

Liquid refrigerant formed in the condenser 215 flows therefrom through a conduit 267 to the upper end of the cooling element 214a, the conduit 267 being formed to provide a trap 268 which is filled with liquid. Liquid refrigerant flows downwardly through cooling element 214a in counterflow to inert gas and is diverted by a dam or barrier 269 at the lower end of this cooling element into the upper end of a conduit 270. From conduit 270 liquid refrigerant is introduced into the upper end of cooling element 214b and flows downwardly through this cooling element in parallel flow with inert gas. In order to drain any liquid which may collect in the outer passage 265 of gas heat exchanger 263, a U-shaped conduit 271 is provided having one leg connected to the lowest part of gas heat exchanger passage 265 and the other leg connected to the upper part of cooling element 214b. Further, a conduit 272 is provided for draining liquid from the outer passage 216 of gas heat exchanger 217 to the absorber vessel 219 at a region below the liquid level therein.

Since inert gas flows successively through cooling elements 214a and 214b and the gas in cooling element 214a contains a lesser amount of refrigerant vapor than in cooling element 214b, the cooling element 214a will operate at a low temperature and cooling element 214b at a higher temperature. By providing the gas heat exchanger 263, inert gas weak in refrigerant and flowing to the low temperature cooling element 214a will be effectively precooled by cool gas passing from the low temperature cooling element 214a to the higher temperature cooling element 214b. In this way the mean or average temperature of cooling element 214a is decreased and that of cooling element 214b is increased due to heat transfer from inert gas flowing in the outer passage 265 to the gas flowing in the inner passage or conduit 266 of the gas heat exchanger 263.

One manner in which the cooling elements 214a and 214b of an absorption refrigeration system like that just described may be positioned in a thermally insulated interior of a household refrigerator cabinet for cooling separate compartments therein is diagrammatically illustrated in Figs. 12 and 13. In Figs. 12 and 13 parts corresponding to those shown in Figs. 9 and 10 are designated by the same reference numerals increased by two hundred.

In Figs. 12 and 13 the space 241 is divided into compartments 255 and 256 by a horizontal partition 273 which may comprise a wall member formed of suitable insulating material. The cooling effect produced by the low temperature cooling element 214a is utilized to effect cooling of the compartment 256 which serves as a freez-

ing section adapted to receive ice trays, frozen food packages and other matter to be frozen.

While ice trays 257 are diagrammatically illustrated as being supported and in thermal contact with the straight portions of the upper looped coil 214a, it is to be understood that plates or other suitable structure may be provided for supporting a number of ice trays and other matter, and that such structure may be fixed in good heat conducting contact with the looped coil 214a after the cooling unit 214 is positioned in the space 241 through the opening 247 in the rear wall 246 of the cabinet 240. The cooling effect produced by the higher temperature cooling element 214b is employed to cool air in the lower compartment 255 and abstract heat from food products which may be disposed on shelving (not shown) disposed in this compartment.

As explained above in connection with the previously described embodiments, the compartment 256 may be provided with a cover (not shown) hinged to the partition 273, for example, to gain access into the freezing section and at other times keep it closed to maintain a low temperature therein. The insulating partition 273 may be formed of separate sections which interlock in any suitable manner, as indicated at 274 in Fig. 13, the separate sections being shaped to fit snugly about parts of the gas heat exchanger 263 connecting the upper and lower cooling elements 214a and 214b.

In view of the foregoing it will now be understood that an improved refrigerator has been provided in which low and higher temperature cooling elements are arranged to cool different compartments, such cooling elements being formed of looped coils each of which is disposed essentially in a single vertical plane. In the embodiments of Figs. 8 to 11 the cooling elements are disposed at opposite sides of a vertical wall member, while in the embodiment of Figs. 12 and 13 the low and higher temperature cooling elements are disposed one above the other at opposite sides of a horizontal wall member and located substantially in the same vertical plane. With such disposition of the cooling elements in the insulated interior of a household refrigerator cabinet, an opening of minimum size is required in a wall of the cabinet for positioning the cooling elements therein when the latter form the cooling unit or evaporator structure of absorption refrigeration apparatus employing an inert gas as a pressure equalizing agent.

By cooling the freezing section of a household refrigerator with the aid of a low temperature cooling element comprising a looped coil disposed essentially in a single vertical plane a steep vertical temperature gradient is avoided. Moreover, by arranging a vertical plate 58a in good heat conducting relation with the looped coil, as seen in Fig. 9, food packages can be rapidly frozen on the plates 58 and thereafter stored in the compartment 56 alongside the plate 58a for substantially the entire depth of the compartment without any danger of thawing in any part thereof. Hence, by employing a vertically extending looped coil which extends upwardly to regions above the bottom of the freezing section for a major portion of the height of this section, an arrangement is provided for effectively storing frozen food packages and other matter to be frozen.

While several embodiments of the invention have been shown and described, it will be apparent to those skilled in the art that various modifications and changes may be made without

departing from the spirit and scope of the invention, as pointed out in the following claims.

What is claimed is:

1. In a refrigerator comprising a cabinet defining an interior and partitioning therein providing separate compartments, an absorption refrigeration system having a circuit for inert gas including cooling elements which always are in open communication with one another and operable at different average temperatures, at least one of said cooling elements being operable at a low temperature for freezing matter and arranged to effect cooling of one compartment at one side of said partitioning adapted to serve as a freezing section, said one cooling element including means providing a vertically extending refrigerant passage which is substantially greater in length than the vertical extent thereof and occupies a major portion of the height of said freezing section, and another of said cooling elements being arranged at another side of said partitioning to effect cooling of a different compartment.

2. An absorption refrigeration system having a circuit for inert gas including an absorber and cooling structure comprising a low temperature cooling element and a higher temperature cooling element, a circuit for absorption liquid including said absorber and a generator, each of said cooling elements comprising means providing an elongated refrigerant passage which is disposed essentially in a single vertical plane, said cooling structure being so connected and arranged in said gas circuit that inert gas enters and leaves at regions removed from the extreme lower part thereof which extends downwardly to a level between the upper part of said absorber and the liquid level therein.

3. An absorption refrigeration system having a circuit for inert gas including a plurality of gas heat exchangers, an absorber and low and higher temperature cooling elements, each of said cooling elements comprising means providing an elongated refrigerant passage which is disposed essentially in a single vertical plane, one of said gas heat exchangers having a first passage connected to receive inert gas from said absorber and a second passage connected to receive gas from said higher temperature cooling element and conduct such gas to said absorber, another of said gas heat exchangers having a first passage connected to receive gas from the first passage of said one gas heat exchanger and conduct such gas to said low temperature cooling element and a second passage connected to receive gas from said low temperature cooling element and deliver such gas to said higher temperature cooling element, said other gas heat exchanger being disposed between and substantially in the same vertical plane as said low and higher temperature cooling elements.

4. A refrigerator comprising a cabinet having the interior thereof subdivided into compartments by partition means including a vertical insulating wall, absorption refrigeration apparatus having a gas circuit including a low temperature cooling element and a higher temperature cooling element, said low temperature cooling element being disposed in one of said compartments and comprising a looped coil having straight horizontally extending portions and connecting bends disposed essentially in a single vertical plane, structure in good thermal relation with said coil providing a vertical wall having a relatively extensive heat transfer surface which extends a major

portion of the distance from the bottom to the top of said one compartment.

5. An absorption refrigeration system having a circuit for inert gas including a low temperature cooling element and a higher temperature cooling element, each of said cooling elements comprising means providing an elongated passage for refrigerant which is disposed essentially in a single vertical plane, means to supply refrigerant fluid to each of said cooling elements for downward flow therethrough, said cooling elements being so connected in said gas circuit that gas flows in parallel with refrigerant in one of said cooling elements and counter-current to refrigerant in another of said cooling elements.

6. An absorption refrigeration system as set forth in claim 5 in which inert gas flows upwardly in said low temperature cooling element and downwardly in said higher temperature cooling element.

7. An absorption refrigeration system having a circuit for inert gas including an evaporator in which refrigerant evaporates in the presence of an inert gas and an absorber, a circuit for absorption liquid including said absorber and a generator, said evaporator being so connected and arranged in said gas circuit that inert gas enters and leaves regions removed from the extreme lower part thereof, and means including a connection for draining liquid from the extreme lower part of said evaporator to said absorption liquid circuit, said connection providing a path of flow for liquid through which inert gas normally does not pass and which communicates with the absorption liquid circuit at a region below the liquid surface level thereof.

8. An absorption refrigeration system having a circuit for inert gas including an evaporator in which refrigerant evaporates in the presence of an inert gas and an absorber comprising a looped coil and a vessel adapted to hold a body of liquid absorbent, a circuit for liquid absorbent including said absorber and a generator, said evaporator being vertically disposed and so connected and arranged in said gas circuit that inert gas enters and leaves regions removed from the extreme lower part thereof which is located at a level between the upper part of said looped coil and the liquid surface level in said vessel, and means including a connection for draining liquid from the extreme lower part of said evaporator to said absorption solution circuit, said connection providing a path of flow for liquid through which inert gas normally does not pass and which communicates with the absorption liquid circuit at a region below the liquid surface level thereof.

9. An absorption refrigeration system having a circuit for inert gas including a plurality of gas heat exchangers, an absorber and low and higher temperature cooling elements, each of said cooling elements comprising means providing an elongated refrigerant passage which is disposed essentially in a single vertical plane, one of said gas heat exchangers having a first passage connected to receive inert gas from said absorber and a second passage connected to receive gas from said higher temperature cooling element and conduct such gas to said absorber, and another of said gas heat exchangers having a first passage connected to receive gas from the first passage of said one gas heat exchanger and conduct such gas to said low temperature cooling element and a second passage connected to receive gas from said low temperature cooling element and deliver such gas to said higher temperature cool-

ing element, one of said cooling elements having at least a part thereof at a level between the upper part of said absorber and the liquid level therein.

10. A refrigerator comprising a cabinet having the interior thereof subdivided into compartments by partition means including an insulating wall, absorption refrigeration apparatus having a gas circuit including a low temperature cooling element and a higher temperature cooling element, said higher temperature cooling element being arranged to effect cooling of one of said compartments, said low temperature cooling element being disposed in another of said compartments and comprising a looped coil having straight horizontally extending portions and connecting bends disposed essentially in a single vertical plane, and said looped coil extending a major portion of the distance from the bottom to the top of said other compartment.

20. 11. In a refrigerator comprising a cabinet having the interior thereof subdivided into compartments by partition means, an absorption refrigeration system including a low temperature cooling element and a higher temperature cooling element disposed at opposite sides of said partition means and arranged to effect cooling of different compartments, and each of said cooling elements comprising means forming an elongated path of flow for circulation of liquid refrigerant and inert gas therethrough to provide a relatively extensive gas and liquid contact surface between the aforementioned fluids, the elongated path of flow of each of said cooling elements being disposed in a single vertical plane.

35. 12. In a refrigerator comprising a cabinet having the interior thereof subdivided into compartments by partition means including a vertical wall, an absorption refrigeration system including a low temperature cooling element and a higher temperature cooling element which are disposed relatively close to and alongside one another at opposite sides of said vertical wall and arranged to effect cooling of different compartments, and each of said cooling elements comprising means forming an elongated path of flow for circulation of liquid refrigerant and inert gas therethrough to provide a relatively extensive gas and liquid contact surface between the aforementioned fluids, the elongated path of flow of each of said cooling elements being disposed in a single vertical plane.

40. 13. Apparatus as set forth in claim 11 in which said partition means includes a horizontal wall and said cooling elements are disposed at opposite sides of said wall and substantially in the same vertical plane for cooling different compartments.

45. 14. In a refrigerator comprising a cabinet having thermally insulated walls forming a space divided into several compartments by partition means, a refrigeration system comprising a condenser in which refrigerant vapor is liquefied and cooling structure, said cooling structure including a low temperature cooling element and a higher temperature cooling element which always are in open communication with one another and operable at substantially the same pressure, said low and higher temperature cooling elements being arranged in the space to effect cooling of separate compartments therein, each of said cooling elements including refrigerant passage forming means which is disposed essentially in a single vertical plane, and conduit means connected to said condenser and to the upper parts of both 50. 55. 60. 65. 70. 75. 80. 85. 90. 95. 100. 105. 110. 115. 120. 125. 130. 135. 140. 145. 150. 155. 160. 165. 170. 175. 180. 185. 190. 195. 200. 205. 210. 215. 220. 225. 230. 235. 240. 245. 250.
